STOKER RISER SCREW

Samuel G. Jones, Princess Anne County, Va., assignor to Berkley Machine Works and Foundry Company, Inc., Norfolk, Va., a corporation of Virginia

Application May 1, 1941, Serial No. 391,268

10 Claims. (Cl. 110—105.5)

This invention relates to locomotive stokers, and more particularly to stokers that deliver coal to a locomotive fire-box through an opening in its backwall.

In stokers of this character coal is fed forward by a conveyor screw from a trough beneath the coal bin on the locomotive tender and is moved upwardly through an inclined riser conduit to a jet member from which jets of steam distribute the coal over the grate in the fire-box. In the ordinary stoker having a conveyor screw in the riser conduit the coal is fed more or less straight ahead over the central portion of the jet member without spreading laterally thereon an appreciable amount. With such concentrated central feeding of the coal it is difficult to obtain uniform spreading of the coal over the grate, and a great deal of steam is required to break up and scatter the heavy stream of coal falling over the central portion of the jet member. In fact, the steam is more likely to merely blow holes through the stream of coal. Due to the narrow stream of coal it is customary to use a relatively narrow jet member because a wider one would serve no purpose. I have found that much more even distribution of coal over the grate can be obtained if the coal is first spread out across the full width of the jet member, and that still better distribution results if a relatively wide jet member is used; provided, the full width of the wide jet member is made use of.

It is among the objects of this invention to provide a locomotive stoker in which improved distribution of coal over the grate is obtained, in which the riser screw spreads the rising coal laterally toward the sides of the jet member, in which a relatively wide jet member can be used advantageously, and in which less steam is required for the jet member than previously.

In accordance with this invention a trough is mounted on a locomotive tender in a position to receive coal from its coal bin and is connected by a tubular conduit and a universal joint to the lower end of an upwardly and forwardly inclined riser conduit that has a widened upper portion opening into the back of the fire-box. To transfer coal from the tender to the fire-box, conveyor screws are rotatably mounted in the horizontal and inclined conduits with their adjoining ends connected together by a universal joint. As the coal leaves the upper end of the riser conduit it passes over steam jets by which it is projected into the fire-box and distributed over the grate. In the enlarged upper portion of the riser conduit the riser screw has a portion adjacent its delivery end which is materially smaller in diameter than its delivery end portion and the portion of the screw at the lower end of the reduced portion, whereby an area is formed in which positive feeding of the coal is reduced

so that the coal will heap or mound up and be spread laterally toward the sides of the jet member by the delivery end portion of the screw. Coal thus flows over the upper edge of the jet member in a thin layer extending across the full width of the jet member, so that a much more uniform distribution of coal over the grate can be obtained than heretofore.

The invention is illustrated in the accompanying drawings in which Fig. 1 is a side view of the front end of my locomotive stoker; Fig. 2 is a front view of the upper end of the stoker taken on the line II—II of Fig. 1 but with the deflector member raised; Fig. 3 is a combined plan and section taken on the line III—III of Fig. 1; Figs. 4, 5, 6, 8, 10 and 12 are plan views of the upper end portions of six modified screws invented by me; and Figs. 7, 9, 11 and 13 are end views of the screws shown in Figs. 6, 8, 10 and 12, respectively.

Referring to Fig. 1 of the drawings, a conveyor trough (not shown) is mounted on a locomotive tender in the usual way below its coal bin in order to receive coal therefrom. Extending forwardly from the front of the trough to a point below the deck 1 of the locomotive cab is a horizontal tubular conduit 2. The front end of the conduit is connected by a suitable universal joint 3 to the lower end of an upwardly and forwardly inclined riser conduit 4 the upper end of which is mounted in rigid position relative to the backwall 6 of the locomotive boiler by bolting the riser to a bracket 7 on the locomotive frame beneath the cab deck.

Coal is fed forward from the trough and through horizontal conduit 2 by means of a conveyor screw 8 that is driven from its rear end by an engine 9 mounted on the locomotive. The front end of this screw is connected by means of a universal joint 11 to the lower end of a riser conveyor screw 12 rotatably disposed in the riser conduit. As shown in Fig. 3, the lower portion of the riser is tubular, but the upper portion flares out and is enlarged or widened to substantially the width of the normal hand-firing opening above it, or the upper end of the riser conduit and the backwall opening with which it communicates may be made wider than the usual hand-firing opening. The rear wall 50 of the enlarged portion of the riser conduit is flat and is provided with an opening that is normally closed by clean-out door 14 hinged at its bottom to the conduit and connected at its top to the conduit by swing bolts 16 pivoted thereto.

To distribute coal over the fire-bed after it reaches the upper end of the riser, a hollow jet member 21 is mounted on the upper end of the riser floor which is provided with a forwardly extended flat portion 22 that serves as a support. The jet member is detachably held in place by

means of bolts 23 that are threaded in the side walls of the riser. As shown in Fig. 1, the rear wall of the jet chamber is inclined and forms a continuation of the adjoining portion of the riser floor, and its front wall is inclined downwardly and forwardly to an apron 24 integral therewith that overlies the bottom of the back-wall opening to protect it from any possible abrasion that might accidentally occur. The lower portion of the jet member is provided with passages connected by pipes 26 to a source of fluid under pressure, such as the steam in the locomotive boiler, and the inclined front wall of the jet member is provided with a plurality of jet orifices 27 from which the steam issues for throwing coal forwardly across the grate. The inside of the jet member is preferably divided by vertical partitions 28 (Fig. 2) into several chambers to each of which steam is delivered by a separate pipe 26 controlled by a manually operable valve 29 so that the pressure in each chamber can be individually regulated to aid in giving control over fuel distribution.

The coal which is thrown upwardly by the steam jets is intercepted and directed forwardly in all directions by a fuel-deflecting member 31 provided with guiding ribs 38. The deflector is supported from its rear end by a horizontal shaft 32 extending therethrough and pivotally mounted in lugs 33 depending from the top wall of the riser. The exposed end of the shaft is provided with a lever 34 for turning it in order to swing the deflector in a vertical plane, and the lever is locked in adjusted positions by any suitable means.

It is a feature of this invention that the forwardly moving stream of coal in the upper portion of the riser conduit is more or less leveled off and spread laterally across the jet member for substantially its full width. Accordingly, in the embodiment of the invention shown in Figs. 1, 2 and 3 the riser screw has a normal or main conveyor thread 41 that extends upwardly from the lower end of the screw hub 42 to a point in the enlarged upper portion of the riser conduit several inches below the upper end of the hub which is above the jet member. Starting a short distance above the upper end of the main thread there is a short thread 43 that winds around the screw hub in the same direction as the main thread. The screw thus has between its two threads a portion of greatly reduced diameter which is free of threads located in the enlarged portion of the conduit behind the jet member. When coal that is being elevated through the riser conduit by the main thread 41 reaches this reduced portion of the screw there is no thread to carry the coal farther and its feed is therefore greatly retarded so that instead of moving ahead at the same rate as the coal behind, it heaps up into a pile that is pushed forward by the oncoming coal. The short flight 43 at the delivery end of the screw digs into this mound of coal and spreads it laterally across the full width of the jet member, so that instead of a relatively narrow and deep stream of coal passing over the central portion of the jet member with little or no coal passing over its side portions, the coal is more or less leveled off into a much thinner layer that passes over the jet member from side to side. As a result, a more uniform distribution of coal over the grate can be obtained, and considerably less steam is required

for scattering the shallow layer of coal across the fire-box.

Spreading of the coal across the jet member before it reaches the short flight at the upper end of the screw can be started by providing the screw hub between its two threads with an enlargement 44 that tapers rearwardly.

With the riser screw shown in Fig. 3, which rotates in a clockwise direction, more coal will be delivered to the left half of the jet member than to its right half. This non-uniform delivery can be compensated for to some extent by drilling the jet orifices 27 at such angles that some of those in the left half of the jet member will throw coal from that side across to the right half of the fire-box to make up for the deficiency there that otherwise might exist. The directions taken by steam issuing from the jets is illustrated in Fig. 3 by the broken lines in front of the jet member.

In the modification shown in Fig. 4, instead of providing the screw with two spaced threads as previously described herein, a continuous single thread 46 extends from end to end of the hub but it is reduced materially in diameter at a point spaced from the upper end of the screw to retard the coal feed in order to permit the coal to mound up so that it can be spread laterally across a jet member by the upper flight of the screw. The same type of continuous thread 46 is used in Fig. 5, but the delivery end portion of the screw hub is provided with an additional short thread 47 disposed about 180° from the other thread. In the Fig. 4 embodiment the delivery end of the screw hub is provided with a forwardly and rearwardly tapered enlargement 48 that helps guide coal laterally away from the hub.

In the embodiment of my invention shown in Figs. 6 and 7, the delivery end portion of the screw hub is not provided with a screw flight, but is flared so that it resembles a cone 51 which directs the forwardly moving coal toward the sides of the jet member. This cone may be hollow, and coal that falls in front of it is moved over the central portion of the jet member by steam issuing from a pipe 52 extending axially through the hub and connected at its lower end in any suitable manner to the steam supply of the locomotive.

The modification shown in Figs. 8 and 9 is similar to that shown in Figs. 6 and 7, but the flared end of the screw hub is provided with radial slots 56 through which coal can pass to reach the central portion of the jet member. This enlarged end of the hub may also be provided with a short thread 57 to aid in feeding the coal. This thread preferably winds around the hub in the direction opposite to that of the main thread 58 and thereby cooperates with the main thread in producing a substantially uniform delivery of coal on both sides of the screw in the manner set forth in my said copending application.

As in the two preceding embodiments, the form of my invention shown in Fig. 10 has a main conveyor thread 61 that terminates short of the upper end of the screw hub 62, and the delivery end portion of the hub is enlarged. However, in this case the enlargement is produced by providing the hub with several radial fins or vanes 63 the outer edges of which flare forwardly. As the screw rotates, these vanes push the heaped up coal towards the opposite sides of the jet member, but some coal moves straight ahead

between the vanes to the central portion of the jet member. The same general type of screw is shown in Figs. 12 and 13, except that only two diametrically opposite vanes 66 are used and these are preferably curved as shown in Fig. 13.

According to the provisions of the patent statutes, I have explained the principle and mode of construction of my invention and have illustrated and described what I now consider to represent its best embodiment. However, I desire to have it understood that, within the scope of the appended claims, the invention may be practiced otherwise than as specifically illustrated and described.

I claim:

1. A locomotive stoker conveyor screw for use in an inclined riser conduit having an enlarged upper portion, the screw comprising a hub and a conveyor thread encircling the hub, the diameter of a portion of said thread which is spaced rearwardly from its delivery end and is adapted to be disposed in the enlarged upper portion of the conduit being materially smaller than the portions of said thread at both ends of said smaller portion to provide an area in which positive feeding of the coal is reduced whereby the coal will mound up and be spread laterally by the delivery end portion of the thread.

2. A locomotive stoker conveyor screw for use in an inclined riser conduit having an enlarged upper portion, the screw comprising a hub having an enlarged delivery end, and a conveyor thread encircling the hub and enlarged end, said thread being tapered in toward the hub at a location which is spaced rearwardly from the delivery end of the thread and which is adapted to be disposed in the enlarged upper portion of the conduit, whereby to provide an area in which feeding of the coal is retarded to permit the coal to mound up and be spread laterally by the delivery end portion of the thread.

3. A locomotive stoker conveyor screw for use in an inclined riser conduit having an enlarged upper portion, said screw being adapted to raise coal through the conduit to a jet member at its upper end, the screw comprising a hub and a conveyor thread encircling the hub for the major portion of its length and terminating short of its delivery end, the delivery end of the screw being formed for pushing the rising coal laterally away from the hub, and the diameter of the screw being reduced between its laterally pushing end portion and said thread whereby to provide an area in said enlarged upper portion of the conduit for coal to mound up in.

4. A locomotive stoker conveyor screw for use in an inclined riser conduit having an enlarged upper portion, said screw being adapted to raise coal through the conduit to a jet member at its upper end, the screw comprising a hub having a delivery end portion formed for directing coal laterally, and a conveyor thread encircling the hub for the major portion of its length and terminating at a point spaced rearwardly from said delivery end portion to provide an intervening area in which the coal will mound up and be spread laterally toward the sides of the jet member by said delivery end portion of the hub.

5. A locomotive stoker conveyor screw for use in an inclined riser conduit having an enlarged

upper portion, said screw being adapted to raise coal through the conduit to a jet member at its upper end, the screw comprising a hub having a forwardly flaring hollow delivery end portion with slots through its sides, and a conveyor thread encircling the hub for the major portion of its length and terminating adjacent the rear end of said flaring portion.

6. A locomotive stoker conveyor screw for use in an inclined riser conduit having an enlarged upper portion, said screw being adapted to raise coal through the conduit to a jet member at its upper end, the screw comprising a hub having a forwardly flaring hollow delivery end portion with slots through its sides, a thread encircling said end portion, and a conveyor thread encircling the hub for the major portion of its length and terminating adjacent the rear end of said flaring portion.

7. A locomotive stoker conveyor screw for use in an inclined riser conduit having an enlarged upper portion, said screw being adapted to raise coal through the conduit to a jet member at its upper end, the screw comprising a hub having a forwardly flaring hollow delivery end portion with slots through its sides, a conveyor thread encircling the hub for the major portion of its length and terminating adjacent the rear end of said flaring portion, and a short reverse thread encircling said flaring portion.

8. A locomotive stoker conveyor screw for use in an inclined riser conduit having an upper end portion that is materially wider than the portion of the conduit leading up to it, the diameter of a portion of the screw which is spaced rearwardly from its delivery end and is adapted to be disposed in said wide upper end of the conduit being materially smaller than the portions of the screw at both ends of said smaller portion to provide an area in which feeding of the coal is retarded whereby the coal will mound up and be spread laterally by the delivery end portion of the screw.

9. A locomotive stoker conveyor screw for use in an inclined riser conduit having an enlarged upper end portion, the diameter of a portion of the screw which is spaced rearwardly from its delivery end and is adapted to be disposed in the enlarged upper portion of the conduit being materially smaller than the portions of the screw at both ends of said smaller portion to provide an area in which feeding of the coal is retarded whereby the coal will mound up and be spread laterally by the delivery end portion of the screw, and the portion of the screw on both sides of said smaller portion including conveyor thread flights.

10. A locomotive stoker conveyor screw for use in an inclined riser conduit having an upper end portion that is materially wider than the portion of the conduit leading up to it, the screw comprising a hub having an enlarged portion near its delivery end in a location adapted to be disposed in said wide upper end of the conduit, a screw conveyor thread winding around said hub from its lower end to a point adjacent the lower end of said enlarged portion of the hub, and a screw flight winding around the delivery end portion of the hub above said enlarged portion thereof.

SAMUEL G. JONES.
